UNITED STATES PATENT OFFICE.

WILLIAM E. SMITH, OF ANSONIA, ASSIGNOR TO THE B. GOODMAN MANUFACTURING COMPANY, OF BRIDGEPORT, CONNECTICUT.

BUCKLE.

SPECIFICATION forming part of Letters Patent No. 337,452, dated March 9, 1886.

Application filed January 5, 1886. Serial No. 187,713. (No model.)

To all whom it may concern:

Be it known that I, WILLIAM E. SMITH, of Ansonia, county of New Haven, State of Connecticut, have invented a new and useful Improvement in Buckles, of which the following is a full, true, and exact description, reference being had to the accompanying drawings.

This invention relates to an improvement in flat-back buckles, which consist, generally, of a buckle-body having forms which form returning-bends, in which an independent pivoted tongue is supported.

My invention will be readily understood from the accompanying drawings, in which similar letters refer to similar parts.

Figure 1 is a perspective view of my buckle. Fig. 2 is a section through Fig. 1 on the line *x x*. Fig. 3 is a view of the buckle-body before the tongue is inserted, and Fig. 4 an end view of the tongue.

The buckle-body is otherwise constructed in any well-known way, but the blank is folded twice at right angles, or nearly so, as shown. Such inwardly-returning bend is shown at *G* 25 *F*, Fig. 3. This bend is not folded uniformly, but the part *G* is bent so as to form approximately part of the plane of the buckle when completed. The part *F* is folded the thickness of the metal lower than the part *G*, so 30 that the tongue may rest therein and its back may lie in a plane substantially parallel to the plane of the part *G*. Slots *H H* are cut through the returning-bends *F G*, and slits *E* are cut from the slots *H* to the edge. The parts *D D* 35 *D D*, forming the edges of the slots *E*, are then bent down so as to approximately meet at a still lower plane than the plane *F*. The tongue *B* is approximately rectangular in shape, and adapted to rest upon the projecting 40 lugs *F F*. These slots *C C*, cut in the edge, form pivotal supports in connection with the parts *D D D D* of the buckle-body. The body being formed as shown in Fig. 3, the tongue *B* is readily snapped into place, and when in 45 position the combined slots *H H* and *C C*, with their surrounding metal portions, form sub-

stantially a pivotal connection. When the buckle is closed, its back is smooth and the different parts form substantially a single plane. This tongue is substantially rectangular in shape and should extend to the lower margin of the parts *F F*, though it might be somewhat cut off; but its lower edge should always be a substantially straight line. I prefer to bend it down a little, as shown at *K*, so 50 as to drop below the lower edges of the parts *F*, but this is not essential.

It is obvious that the particular method of pivoting or the supporting of the tongue on the lugs is not essential in the making of a 55 flat-back buckle, though I prefer the devices shown, the essential feature of one part of my invention being to have a pivoted rectangular tongue, which, when closed, shall be substantially flat, and its back shall substantially correspond with the plane of the other parts of the back of the buckle.

What I claim as my invention, and desire to secure by Letters Patent, is—

1. The combination of the buckle-body *A*, 70 having the re-entering folds *F G*, the lugs *F* being depressed below the level of the parts *G*, the parts *F G* being provided with tongues *D D D D*, and the tongue *B*, provided with slots *C C*, resting when closed on the depressed 75 lugs *F F*, thus forming a flat-back buckle, substantially as described.

2. The combination of a buckle-body, *A*, and a tongue, *B*, pivoted in said buckle-body, substantially as described, the back of said 80 tongue being substantially rectangular in shape, and when closed lying in a plane substantially parallel with the back of the buckle, thus forming a flat-back buckle without wearing edges, substantially as described. 85

In testimony whereof I have signed my name to this specification in the presence of two subscribing witnesses.

WILLIAM E. SMITH.
